Fig. 6.

UNITED STATES PATENT OFFICE.

HJALMAR G. CARLSON, OF WORCESTER, MASSACHUSETTS, ASSIGNOR TO ROCKWOOD SPRINKLER COMPANY OF MASSACHUSETTS, OF WORCESTER, MASSACHUSETTS, A CORPORATION OF MASSACHUSETTS.

MITER BOX.

Application filed January 7, 1925. Serial No. 1,120.

The principal objects of this invention are to provide a metallic frame for a miter box which can be formed of sheet metal in a rapid and inexpensive manner and to provide an improved means for supporting the saw guide and adjusting it to any desired height or to any desired angle.

Other objects and advantages of the invention will appear hereinafter.

Reference is to be had to the accompanying drawings in which—

Fig. 1 is a plan of a miter box constructed in accordance with this invention;

Fig. 2 is an end view of the same;

Fig. 3 is a front elevation showing two positions of the saw guide;

Fig. 4 is a plan of the adjusting arm removed from the machine;

Fig. 5 is a fragmentary front view of the rack with which this arm co-operates;

Fig. 6 is a view like Fig. 2 showing a modification;

Fig. 7 is a plan of a part thereof;

Fig. 8 is a sectional view on the line 8—8 of Fig. 7; and

Figs. 9 and 10 are rear views of two of the elements thereof.

The frame of the miter box in the form illustrated comprises a flat plate or platform 10 having its two ends bent down at right angles to form four legs 11, these legs having supporting feet 12 formed by bending them inwardly preferably and therefore integral with the platform. At the rear the sheet metal of which the platform 10 is formed is bent up to form a back plate 13 at right angles and this is provided with a slot 14 through which the saw passes in the operation of the device. On the front the platform is provided with an integral flange 15 extending downwardly all the way across the front and cut off at right angles at the ends to engage the ends 11 and strengthen the structure in that way. This flange is of the same depth throughout so as to finish the article properly in front. It is provided with an arcuate portion 16 at the center of the front provided with a series of notches 17 in the bottom to constitute a rack for controlling the position of the saw guide as will appear.

Located at the center of curvature of this rack is a vertical stud or shaft 19. This can conveniently be in the plane of the back

plate 13 as shown. Pivoted on this stud is a horizontal operating arm 20 separated from the bottom of the platform by a washer 21 on the stud 19. This so-called washer is really fixed with respect to the frame which has a semi-circular projection 22 under the head of the stud for engaging the upper side of the so-called washer. Another washer can be used on the bottom of the arm 20. This arm is provided with a pair of fingers 23 at its outer end coming just inside the flange or rack 16 and with a projection 24 extending beyond them and projecting upwardly. This latter has a screw-threaded opening in which there is a binding screw 25, the end of which is adapted to come against the face of the rack 16 and hold this arm in adjusted positions. The arm is provided with an integral prong 26 adapted to engage in the notches 17 to hold the arm in adjusted positions. These notches are naturally so arranged as to provide for sawing at various angles as for example 45 degrees and 30 degrees or anything else that happens to be common in the industry in which the instrument is used. The arm 20 is thinned across it at 27 to permit it to yield. It is located so as to yieldingly hold the prong 26 in any notch 17 and so it will snap into them.

The arm 20 projects beyond the point of pivotal support and is provided at a point materially beyond the stud with a perforation through which extends the threaded end of an upright standard 28 with a nut 29 on the bottom to hold it securely in position. This standard is transversely perforated at the top by a round hole to receive an arm 30 of cylindrical form preferably. The top of the standard 28 is slit at 28^a and provided with a binding screw 31 so that this arm 30 can be moved out or in or turned on its own axis and then secured in the desired position. This arm is intended to extend forward over the platform of the miter box.

On the outer end the arm 30 is provided with a longitudinal diametrical slot for receiving a plate 33. This plate is shown in the present case arranged vertical and as having upper and lower flanges 34 parallel with each other. These flanges are provided with T-shaped slots for receiving one

of a pair of arms 35 which are integrally connected together at the top by being bent from the same piece of bar stock. It constitutes a horse shoe shaped member having two holding arms for a pair of saw-guides 36 which are secured to their lower ends. It will be obvious that this entire saw-guide can slide up and down in the slots in the flanges 34. The arm 30 is provided with a thumb-screw 37 for engaging the plate 33 and securing it in adjusted positions. On the metallic platform of the miter box is fastened a board 40 for receiving the teeth of the saw so as to avoid the dulling of the saw on the metal platform.

In the use of this device the arm 30 can be moved out or in by loosening the screw 31, the arm 35 can be moved up and down by loosening the screw 37 and the whole guide can be moved around at any angle desired within reasonable limits by pressing down on the outer end of the arm 20 and swinging it around. Then it can be secured by means of the screw 25. These are the ordinary adjustments in miter boxes and they are all provided for in this case by very simple means and by inexpensive construction. There is one other adjustment that can be provided. That is to loosen the screw 31 and turn the guide 35 with the arm 30 to any desired angle as indicated in dotted lines in Fig. 3.

It will be noted that in all positions in which the saw guides are vertical the saw will pass through the slot 14 irrespective of the adjustment of the guides around the arc of the circle. This is due to the fact that the arm 20, which carries both the standard 28 and all the parts supported by it is pivoted at the center of the slot 14.

In the form shown in Figs. 6 to 10, many of the parts are the same as those above described and have been given the same reference numerals, but in place of the two parts 28 and 30, I have shown a rod 41 which is bent at right angles and has a central axial cavity 42 in its horizontal end surrounded by a conical surface 43 having a scale on it. On the rear of the horizontal arm 41 near this scale is a slot 44 extending clear through to the recess and extending about one third of the way around the circle.

Covering or partially covering this slot is a plate 45 having an arcuate shape and a roughened or toothed interior concave surface. This curved plate has a central opening 46 through which extends a thumb screw 47 screwing into the end of a rod 48 which is in axial alignment with the end of the arm 41 and constitutes the equivalent of the rod 30. This rod has a reduced end which extends into the recess 42 and at the shoulder is provided with a zero point, as shown, registering with the scale on the conical end 43 so as to show whether the supporting arm

48 is turned at an angle or not. This arm 48 supports the plate 33 and will hold the saw guides 36 in exactly a vertical position when the two zero points are together, as shown in Fig. 7. Obviously the thumb screw 47 may be loosened and the rod 48 turned on its own axis in either direction and then the screw tightened up again to hold it there and then the scale will show the angle.

In either form this constitutes an extremely durable miter box which can be used for all ordinary operations that may be required and will not get broken up in the way in which ordinary miter boxes frequently are. These parts are substantially connected so that in operation it will retain its accuracy and there is not enough flexibility of any of the parts to permit the guides 36 getting out of true.

Although I have illustrated and described only one form of the invention I am aware of the fact that modifications can be made therein by any person skilled in the art without departing from the scope of the invention as expressed in the claims.

Therefore, I do not wish to be limited to all the details mentioned, but what I do claim is:—

1. As an article of manufacture, a miter box comprising a sheet metal platform bent up at the back to form a back plate and bent down at the front to form a curved flange having notches on the bottom, an arm pivoted under the rear of the platform at the center of said back plate extending to the front and having an integral prong at the top for engaging in said notches, said front flange being curved on the pivot as a center, and means carried by said arm and movable therewith for guiding a saw.

2. In a miter box, the combination with a frame and back plate, the latter having a vertical slot, of an arm pivoted to swing about the center of said slot and having a spur at the front thereof, the front of the miter box having an arcuate flange extending downwardly therefrom provided with notches in the bottom to receive said spur so that the notches can control the position of the arm about its center, means carried by the arm for clamping it to the flange in adjusted positions, said arm having a portion between its pivot and its forward end thinned down to give it resiliency to allow the spur to engage the notches, and a saw guide carried by the other end of the arm.

3. In a miter box, the combination with a sheet metal frame and back plate, the latter having a vertical slot, of a vertical shaft or stud at the center of the bottom of said slot, an arm pivoted to swing on said stud under the frame and having at the front thereof two fingers extending upwardly and a projection extending upwardly at a greater distance from the point of pivotal

- support, a screw on said projection for clamping the arm in adjusted positions, the front of the miter box having an arcuate flange extending downwardly therefrom between the fingers and projection and provided with notches in the bottom and said arm having a spur registering with said notches so that the notches can control the position of the arm about its center, said arm having a portion between its pivot and forward end thinned down to give it resiliency to allow the spur to spring into and out of the notches, and a saw guide supported by the other end of the arm.
- 15 4. In a miter box, the combination with a frame and an arm pivoted at the rear there-
- of, of a standard extending up from the arm and fixed thereto, said standard having a circular passage through it arranged horizontally and having a slit end, a round bar adjustable in said passage and extending forwardly over the arm, a guide on said bar, a pair of saw guides, means for supporting the saw guides from said guide, and means for clamping said supporting means in adjusted positions, whereby the saw guides may be turned about a horizontal axis above it to any angular position.

In testimony whereof I have hereunto affixed my signature.

HJALMAR G. CARLSON.
